DESIGN FOR A COMBINED FROZEN CONFECTION AND HANDLE

Morris Lazow, Brooklyn, N. Y.

Application January 12, 1938, Serial No. 74,256

Term of patent 14 years

To all whom it may concern:

Be it known that I, Morris Lazow, a citizen of the United States, residing in the Borough of Brooklyn, county of Kings, city and State of New York, have invented a new, original, and ornamental Design for a Combined Frozen Confection and Handle, of which the following is a specification, reference being had to the accompanying drawing, forming a part thereof, in which:

Fig. 1 is a perspective view of a combined frozen confection and handle showing my new design;

Fig. 2 is an end elevation thereof;

Fig. 3 is a top plan view; and

Fig. 4 is a side elevational view thereof.

I claim:

The ornamental design for a combined frozen confection and handle as shown.

MORRIS LAZOW.
